UNITED STATES PATENT OFFICE

FRED A. HANSEN, OF MILWAUKEE, WISCONSIN, ASSIGNOR TO HEVI DUTY ELECTRIC COMPANY, OF MILWAUKEE, WISCONSIN, A CORPORATION OF WISCONSIN

CONVEYER

Application filed January 23, 1928. Serial No. 248,927.

My invention relates broadly to a conveyer and more particularly to a movable carrier adapted to heat treatment furnaces, either of the fuel-fired or electrically heated type.

5 The object of my invention is to provide a conveyer for heat treatment furnaces that will withstand high temperature heat action and which will have the least tendency to mar or scratch the articles being conveyed through 10 the heat treatment furnace.

A further object of the invention is to provide a construction of conveying means for heat treatment furnaces whereby no portion of the articles being heat treated is constantly 15 in contact with the conveying mechanism.

A further object of the invention is to provide a conveyer construction having the conveying parts formed from comparatively short pieces of stock to lessen the probability 20 of distortion and warpage under heat action, and to have the parts readily replaceable.

Still another object of the invention is to provide a construction of conveyer for heat treatment furnaces superior to the chain conveyers and so-called rocking-beam conveyers heretofore employed which are not economical in operation due to heavy heat conduction losses in their operation.

A further object of my invention is to provide a mechanism for a heat treatment furnace by which articles may be advanced through the furnace upon a set of reciprocating beams, means being provided to raise the articles from the beams in timed relation to 35 the reciprocating movement of the beams so that the articles are carried forward upon each longitudinal movement of the beams in one direction and maintained out of contact with the beams, while the beams are returning to their initial position and subsequently restored upon the beams for a further longitudinal movement over a predetermined time period.

Other and further objects of my invention 45 reside in the construction and arrangement of furnace mechanism described in the following specification and illustrated in the accompanying drawings, in which:

Figure 1 is an end elevation of the furnace 50 structure partially broken away and illus-

trated in cross-section; Fig. 2 is a longitudinal vertical section through the furnace structure on line 2—2 of Fig. 1; Fig. 3 is a diagrammatic view taken on line 3—3 of Fig. 2 showing the arrangement of shafts forming 55 the actuating mechanism for the conveyer of my invention; Fig. 4 is a lateral cross-sectional view through the furnace structure on line 4—4 of Fig. 2; Fig. 5 is a plan view of the structure of the auxiliary beam system 60 employed in the conveyer; Fig. 6 is a side elevation of the auxiliary beam structure employed in the conveyer system of my invention; Fig. 7 is a side elevation showing the structure of the operating cams for the auxiliary beam structure showing the lower extremity of the lifting rods; Fig. 8 is a cross-sectional view through the operating cam and lifting rod of Fig. 7; Figs. 8^a and 8^b are diagrammatic views explaining my invention; 70 Fig. 9 shows the arrangement of the abutting end of one of the crank arms with the end of the beam structure; and Fig. 10 is a cross-sectional view of one of the sections constituting the conveyer. 75

Referring to the drawings in more detail, the furnace structure is shown elevated from a supporting base with mechanism disposed beneath the structure and extending horizontally for the distance through which the articles to be heat treated are passed. 80

The furnace consists of an outer shell 7 containing refractory insulation walls 8, containing a heating chamber 9, shown heated electrically by means of coils 28 in apertures 85 at the bottom of the furnace chamber following customary practice of the art. Heating coils can also be shown as installed on the side walls 29 and arch 30, as set forth more particularly in Letters Patent No. 1,614,321, 90 to E. L. Smalley, dated January 11, 1927.

The conveyer consists of sections of horizontally conveying rails 3 extending longitudinally through the furnace, and lifting rails 10 extending longitudinally through the furnace. The preferred form of each section of the conveyer is shown in Fig. 10 where three webs are angularly disposed with respect to each other as shown. This shape permits of three interchangeable positions for support- 100

ing the material being conveyed. Faces 44 which engage bearing plates or seats 45, tend always to keep angular edges 46 knife-edged shape. These knife edges permit of the best 5 convection and improve the heat treatment properties of the furnace.

The bearing plates or seats 45 are mounted upon pedestals 50 positioned at intervals along the length of the furnace. The sections 10 of the conveyer abut end to end and are slideable to the seats, each section overlapping two of the bearing plates 45. The bearing plates have such a length that the sections of the conveyer extend over the bearing plates for 15 a substantial distance at each limit of longitudinal movement of the conveyer sections. By reason of the sectional construction of the conveyer the parts in the conveyer may be readily renewed as the rails become worn 20 from time to time in addition to the fact that each section of the rails may be reversed to present a new supporting web to the material whenever the sections may become worn.

In Figs. 1 and 2, reference character 11 25 designates an electric motor transmitting power through spur gear 12 to a speed reducer 13, and a gear reduction 14, through chain 15 to shaft 16 extending longitudinally below the furnace. On shaft 16 are shown 30 mitre gears 17 engaged with bevel gears 18 which are mounted on transverse shafts 19. On transverse shafts 19 are shown cams 5 engaging rollers 21 on the bottom of lifting shafts 4. On the other transverse shafts 22 35 are mounted other cams 23, engaging rollers 51 at the bottom end of pushing levers 6. It will thus be seen that a vertical or lifting motion is imparted to lifting rods 4, corresponding to the difference between the shortest and greatest radii of cams 5. Similarly, motion 40 is imparted to levers 6 by means of cams 23.

Cams 5 are so designed and mounted on transverse shafts 19 that no action is imparted to lifting rods 4 while cams 23 are 45 imparting a motion to levers 6, thereby leaving rails 10 inactive while conveying rails 3 are in motion.

Material to be conveyed by rails 3 is, therefore, moved in successive steps through the 50 furnace and lifting rails 10 lift the work free from rails 3 while rails 3 are in motion. Because the top edge of rails 3 are above the horizontal plane of rails 10, the material being conveyed is not in contact with rails 10 except when rails 10 are lifting. This operation is clearly shown in the diagrammatic views Figs. 8^a and 8^b. In Fig. 8^a the article A under heat treatment is being advanced through the furnace on rails 3. In Fig. 8^b 55 rails 10 have raised article A from rails 3 and rails 3 can swing back to a position where article A can be restored for the succeeding advance movements.

Mounted on each end of the furnace shell, 60 I provide a yoke casting 25 having a plurality

of holes 26 through which a pin 27 can be inserted, thereby providing a movable fulcrum 27 for levers 6. In lever 6 are provided holes 31 corresponding to holes 26 in yoke 25 for receiving pin 27.

In the bottom casting 32 of lifting rods 4 is 70 shown a roller 21 revolvable about pin 34 and in the arms which are integral with casting 32, there are pins 35 engaged in grooves 36, following the contour of the sides of cams 5. If, for any reason, lifting rods 4 do not descend by force of gravity, pins 35 engaged in 75 grooves 36 will exert a positive downward force on lifting rods 4 to keep wheels 21 in contact or in near contact with cams 5.

Lifting rails are provided at one end on the 80 under face with lugs 37, which lugs are engageable with the hollow end of lifting rods 4, being shown in tubular form in Fig. 6. These lugs 37 keep rails 10 in constant alignment. When rails 10 are assembled as shown 85 in top plan, Fig. 5, ends 38 of rails 10 are free to expand by heat action, but are kept in proper alignment by means of slots formed in the walls of rod 4 at 39.

In Fig. 9 is shown a head 40 adjustable by lock nut 41 on threaded portion of adjustable head 40. The upper extremity of lever 6 is tapered at 43 to receive threaded stud 42. The adjustment of heads 40 permits leaving a predetermined clearance between head 40 and the ends of conveying rails 3. The adjustment of this head, therefore, provides a means for overcoming the effect of different 90 expansions which might exist in the several conveying rails in any one furnace. Each rail 3 will be progressed in an amount equal to the action of lever 6 less the space 20 between adjustable head 40 and the ends of rails 3. The lower end of lever 6 is provided with a roller 51 which contacts with the surface of cam 23 and is rocked by the rotation thereof in accordance with the shape 95 of the cam surface.

It will be noted that from a given action, as 100 by one revolution of cam 23, the resulting action can be altered by changing the location of the pin 27 in yoke 25 and lever 6, because the load arm and power arms of lever 6 are thereby alterable at will, or if preferred, 105 the speed may be changed by adjustment of the speed reducer 13.

The operation of the beams or rails 3 is 110 so timed with respect to the operation of the auxiliary beam 10 that articles normally resting upon the beams 3 are carried forward for the distance of longitudinal movement of the rails 3 and then raised clear of the beams 3, while the beams 3 are returning by 115 backward movement. When the beams have 120 returned to initial position, the auxiliary beams 10 drop down and restore the articles which are being heat treated to the beams 3 preparatory to the next successive step 125 through the furnace. It will therefore be seen 130

that material may be subjected to heat treatment over a predetermined time period where the material is advanced step by step by an amount readily controllable by predetermined adjustment of the head 40.

5 It will be observed that the conveyer of my invention avoids the disadvantages of chain conveyers and rocking-beam conveyers. The articles being heat treated are intermittently in contact with the conveying mechanism and are progressed through the furnace in a manner by which the maximum effect from the heat treatment may be obtained.

10 15 The structure of my invention has been found to be extremely practical and while I have described a preferred embodiment of the conveyer mechanism, I desire that it be understood that modifications may be made 20 and that no limitations upon my invention are intended other than are imposed by the scope of the appended claims.

What I claim as new and desire to secure by Letters Patent of the United States is as 25 follows:

1. In a system for heat treatment, a furnace structure, a plurality of beams extending through said furnace structure for carrying articles to be subjected to heat treatment,

30 a drive shaft, a plurality of cams mounted on said drive shaft, rocker arms pivotally mounted at opposite ends of said furnace structure, the extremities of said rocker arms engaging cams at the ends thereof and eng-

35 gaging the ends of said beams at the other extremities thereof for imparting reciprocatory motion to said beams in a substantially horizontal plane, auxiliary beams positioned intermediate said first mentioned beams, and 40 means extending between cams actuated by said drive shaft and said auxiliary beams for imparting vertical movement thereto in timed relation to the reciprocatory movement of said first mentioned beams.

45 2. In a conveyer structure for furnaces, a plurality of supporting members positioned at intervals through said furnace, seats formed on said supporting members, longitudinally extending beams comprising a plurality of 50 independent sections extending between adjacent seats with their ends in abutment and slidably supported on said seats, each of said sections comprising a plurality of angularly disposed webs, two of said webs riding 55 in sliding engagement with said seats and another of said webs providing a carrier surface for articles being subjected to heat treatment.

60 3. In a conveyer structure for furnaces, a plurality of supporting members positioned at intervals through said furnace, seats formed on said supporting members, longitudinally extending beams comprising a plurality of independent sections extending between adjacent seats with their ends in abutment and

slidably supported in said seats, each of said sections constituted by three angularly disposed webs, two of said webs constituting a support for the third web and slidably engaging said seats, the third web extending vertically and operating to carry articles being subjected to heat treatment.

70 4. In a conveyer for furnaces, a furnace structure, a plurality of reciprocatory beams extending through said furnace structure, rod 75 members vertically movable adjacent said reciprocatory beams, said rod members providing supports for sections of a rail extending parallel to said reciprocatory beams, the end of each of said sections lying adjacent 80 each other in the extremities of said rod members whereby said sections may be moved vertically with respect to said reciprocatory beams in accordance with the movement of said rod members.

85 5. In a conveyer for furnaces, a furnace structure, a plurality of reciprocatory beams extending through said furnace structure, a plurality of vertically extending members positioned adjacent said beams, means for imparting vertical movement to said vertically extending members, a plurality of rail sections each having lugs adjacent the ends thereof arranged to fit into the upper extremities of said vertically extending members 90 and each overlapping to form a continuous rail parallel to said reciprocatory beams, whereby said sections may be moved vertically with respect to said reciprocatory beams in accordance with the movement of 100 said vertically extending members.

95 6. In a conveyer for furnaces, a furnace structure, a plurality of reciprocatory beams extending through said furnace structure, a plurality of vertically extending members 105 positioned adjacent said beams, means for imparting vertical movement to said vertically extending members, each of said members being grooved at its upper extremity, a plurality of rail sections having their ends overlapping and having downwardly depending lugs thereon, the overlapping ends of said rail sections being arranged to fit within the grooved extremities of said members, with the lugs thereon protruding to a position 110 within said members, whereby said sections form a substantially continuous rail vertically movable in accordance with the motion of said members.

115 7. In a conveyer for furnaces, a furnace structure, a plurality of beams extending through said furnace structure, means for mounting each of said beams for reciprocatory movement in said furnace structure, 120 brackets supported adjacent the ends of said furnace structure, levers adjustably fulcrumed in said brackets, and means for moving one end of each of said levers for engaging the ends of each of said beams at the op- 130

posite end of each lever for imparting reciprocatory forces to each of said beams.

8. In a conveyer for furnaces, a furnace structure, a plurality of beams extending through said furnace structure, means for mounting each of said beams for reciprocatory movement in said furnace structure, brackets supported adjacent the ends of said furnace structure, levers adjustably fulcrumed in said brackets, means for moving one end of each of said levers for engaging the ends of each of said beams at the opposite end of each lever for imparting reciprocatory forces to each of said beams, and means for variably controlling the rate of movement of said levers for correspondingly controlling the reciprocatory speed of said beams.

9. In a conveyer for furnaces, a furnace structure a plurality of beams extending through said furnace structure for supporting articles to be heat treated, means for mounting said beams for reciprocatory movement, and rockable levers pivotally mounted adjacent the end of said furnace structure, means for imparting variable movement to the lower ends of said levers, and adjustable heads carried by the upper ends of said levers and providing abutments with the ends of said beams for imparting reciprocatory movement to said beams.

10. In a conveyer, a furnace structure, a plurality of beams extending through said furnace structure for supporting articles to be heat treated, means for slidably mounting said beams for reciprocatory movement, and adjustably fulcrumed levers mounted adjacent opposite ends of said furnace structure, each of said levers having a projectable and retractable head for forming an abutment with the ends of said beams, and means for imparting variable speed to the lower ends of said levers at a predetermined rate for correspondingly imparting reciprocatory forces to said beams at a selected rate.

11. In a conveyer structure for furnaces, a furnace structure, a plurality of beams extending through said furnace structure for supporting articles to be heat treated, means for mounting said beams free for reciprocatory movement and rockable levers pivotally mounted at one end of said furnace structure and engaging the ends of said beams for imparting reciprocatory motion to said beams.

12. In a conveyer structure for furnaces, a furnace structure, a plurality of beams extending through said furnace structure for supporting articles to be heat treated, means for mounting said beams free for reciprocatory movement, and rockable levers pivotally mounted at each end of said furnace and engageable with the ends of said beams, the levers being actuated at each end of said furnace structure in timed relation to impart reciprocatory motion to said beams.

13. In a conveyer structure for furnaces, a

furnace structure, a plurality of beams extending through said furnace structure for supporting articles to be heat treated, means for mounting said beams free for reciprocatory movement, and rockable levers pivotally mounted at one end of said furnace structure and engaging the ends of said beams, and means for varying the length of stroke of said levers for controlling the rate of reciprocatory movement of said beams.

In testimony whereof I affix my signature.
FRED A. HANSEN.
